UNITED STATES PATENT OFFICE.

ERNEST C. WILCOX AND BENJAMIN A. SPITZER, OF MERIDEN, CONNECTICUT, ASSIGNEES TO THE CONNECTICUT TELEPHONE & ELECTRIC COMPANY, INC., OF MERIDEN, CONNECTICUT, A CORPORATION OF CONNECTICUT.

SNAP-SWITCH.

1,169,099.

Specification of Letters Patent.

Patented Jan. 18, 1916.

Application filed June 22, 1914. Serial No. 846,454.

To all whom it may concern:

Be it known that we, ERNEST C. WILCOX and BENJAMIN A. SPITZER, citizens of the United States, residing at Meriden, New Haven county, State of Connecticut, respectively, have invented certain new and useful Improvements in Snap-Switches, of which the following is a full, clear, and exact description.

10 This invention relates to "snap" switches as designed, with particular reference to compact arrangement and convenience of operation, as well as the improved structural features as hereinafter pointed out.

15 Specific structural embodiments of the invention are illustrated in the drawings accompanying and forming part of the specification and in which—

Figure 1 is a longitudinal sectional view 20 through one form of a single unit switch construction in accordance with the present invention and shown as applied to the dash on a motor vehicle. Fig. 2 is a detail perspective view of the contact parts of the 25 switch, the housing for the switch parts being indicated in dotted lines. Fig. 3 is a rear end elevation of the switch shown in Fig. 1. Fig. 4 is a transverse vertical section on the line 4—4 of Fig. 1. Fig. 5 is a 30 diagrammatic plan view of a plural unit switch mechanism composed of interconnected units as shown in Fig. 1. Fig. 6 is an end elevation of a modified form of plural unit switch. Fig. 7 is a diagrammatic 35 plan of a further modified form of plural switch and of switch circuit. Fig. 8 is a transverse vertical section on an enlarged scale through the plural unit shown in Fig. 7. Fig. 9 is a diagrammatic plan of a 40 switch and circuit constituting a modification of the circuit of Fig. 7.

Before discussing the detailed structure shown in the drawings, we would have it understood that the switch construction shown 45 and described herein is one which not only possesses structural advantages as switch mechanism *per se*, but is so designed and constructed as to enable single units to be coupled into gangs, and which is also susceptible of wide variation and modification 50 to meet different circuit conditions.

In the accompanying drawings, and with reference particularly to Figs. 1 to 4, 1 designates a tubular casing of insulating

material such as rubber, the base of this casting being relatively thick to afford a suitable anchorage for the contact elements. In the preferred form, the structure of each of these contact elements is the same and we will, therefore, describe specifically only one 55 of these elements, it being understood, of course, that they are spaced at their anchored ends and insulated from each other by the insulating material of the base, and that their contact ends are likewise spaced 60 as will be evident. The contact members are preferably in the form of spring finger contacts and embody a tubular stem portion 2 interiorly threaded, the inner end of the stem portion terminating in a hexagonal 65 nut or abutment 3. The outer end of this tubular portion 2 is originally of greater 70 length than the overall length of the finished stem portion, and is utilized as a means for providing an end electrical connection or terminal for its contact member. A sleeve 4 fits over the stem portion 2, this 75 sleeve being positioned adjacent the outer end of the tubular portion 2, and the extended end of the tubular portion 2 being 80 upset against the face of this sleeve, these parts forming an abutment complementary to and spaced from the hexagonal portion 3 of the stem. A screw 5, forming a binding 85 post, fits in the threaded interior of the tubular portion 2 and is arranged to hold a connector clip or wire between its head and the exposed outer flanged end of the stem portion of the contact. The contact proper 90 comprises a spring finger 6 having its end inturned at 7 to form a contact end for engagement with a reciprocating bridging plunger hereinafter described. The outer 95 end of this spring finger is securely seated and held in a slot cut in the hexagonal abutment 3. In practice two or more of these contact members will be used in switch units. In the specific structure under discussion only two are used, these being suitably secured in the insulating base of the 100 casing 1, so that the spaced abutments formed by the flanges on the stem portions of the contacts form thrust receiving anchorages for the contacts and serve to hold the same rigidly positioned relative to each 105 other, to the casing, and to the bridging contact member hereinafter described. The outer face of the casing is preferably pro-

vided with an insulating wall or walls 1^a to insulate the terminal connections of the contacts from each other. The outer and open end of the casing 1 is preferably provided with tubular bushings 8 molded therein and interiorly threaded, so that a suitable finish plate 9 may be secured to the open end of the casing 1, this plate likewise serving as a guide for a reciprocating contact-bridging plunger 10. This plunger is preferably formed with a metallic current conducting shank or core 11 (see Fig. 1) having a rounded nose 12 arranged to engage and spread apart the ends 7 of the spring contacts.

Rearwardly of the nose, the shank is depressed as at 13, to form a contact socket or depression to receive the end 7 of the contact springs. Rearwardly of this depression the shank 11 is reduced in diameter and extends out through a suitable aperture in the cover plate 9, and has a head 14 of insulating material molded thereon. This reduced shank portion from the depression 13 rearwardly is provided with a covering of insulating material, such as a hard rubber composition, and is shaped to provide immediately adjacent to the depression 13, a ridge 15 forming an upward continuation of the depression, the insulation extending up to, preferably, the highest point of this ridge, and, of course, in the direction of the depression. This ridge 15 is of such diameter that when it engages the ends 7 of the spring contacts, it will expand or spring them apart to a substantial degree, so that these ends when they pass beyond the ridge 15, will snap into the depression 13 which is shaped to correspond to these ends 7 and, therefore, forms with them a lock for the plunger in this position. By having the insulation extend to highest point of the ridge 15, a rubbing or sliding contact with the current conducting metal shank 13 is prevented, and a positive "snap" action is secured. The insulation rearwardly of the ridge 15 is preferably shaped to provide a socket or depression 16, so that the plunger will be held by the depressions 13 and 16 in its "in" and "out" positions respectively. The head 14 forms a push button, so that the switch may be readily controlled by the finger. Such a push button snap switch as described is very advantageous when used in connection with lights of a motor car, a single switch such as heretofore described being adapted to control either the front lighting or the rear or tail lighting, and the switch being susceptible of rearrangement to suit various lighting circuits and conditions. One such illustration is shown in Fig. 5 wherein a plurality of switch units 17 constructed in accordance with the single unit heretofore described, are associated together in series as a plural unit

switch with their adjacent contact terminals on one side connected by a bus bar 18, so that the plural unit switch may be utilized to control the head, side, dash and tail lights of a motor car when the plungers of the various units are pulled out to contact making position. In this connection, it will be seen with particular reference to Fig. 1, that when the plunger is in the "out" position shown in full lines in Fig. 1, the metal of the portion 13 of the shank of the plunger forms a conductor bridging the contact ends 7 and closing the circuit through the connecting wires attached to the binding posts 5. These units in a plural unit construction need not be physically separate, but may be cast in a single base as shown in Fig. 6, wherein 19 designates a single base of insulating material in which are held the four separate electrical switch units such as shown in Figs. 1 and 2, these units as thus formed being, of course, insulated from each other and their terminal contact connections on one side being interconnected by the bus bar 20 as in the form shown in Fig. 5.

We have heretofore stated that a number of spring contacts may be varied. This is true both as to single switch units and as to plural switch units. In Figs. 7 and 8 we have shown a plural unit construction, and, diagrammatically in Fig. 7, a lighting circuit controlled thereby. This plural unit construction, in the present showing, comprises two switch units 21, suitably connected as in the manner heretofore described, to a finishing plate 22 (Fig. 8), the contact springs 23 of these units being three in number and of the same construction as the contact springs heretofore specifically described, and the contact ends 24 of the springs being in the same plane. The contact bridging plunger 25 is of the same construction as the single contact plunger shown particularly in Figs. 1 and 2 and the make and break will be accomplished in the same general manner. By connecting adjacent contact terminals of each unit and at opposite sides by bus bars 26, having a single terminal connector 27 for each bus bar, the circuits controlled by each unit will overlap, and one unit, when the plunger is in contact bridging position, may be utilized to control the head and tail lights of a motor car while the other unit may be utilized to control the side and tail lights of the same car, that portion of the circuit in common to the two units being that including the tail light. By pushing in one unit button and pulling out the other, the current may be sent through either the head and tail lights or the side and tail lights, or by pulling out both buttons the current may be sent through all the lights. As in the first form of the switch described, the base of the casing of the units is preferably provided with

an insulating wall 28 between the various terminal connectors of the contacts.

In Fig. 9 a modification of the switch mechanism shown in Figs. 7 and 8, consists in dispensing with the bus bar 26 and contacts 27 as service terminal connectors and in utilizing a single bus bar 29 on one side of the units 30 to connect these units, thereby enabling the switch to be used in connection with a two-wire system such as diagrammatically shown in Fig. 9, and as contrasted with the wire system shown in Fig. 7.

We have not herein attempted to trace out the various circuits through the lights shown as these circuits, *per se*, form no part of the present invention, and are merely illustrative of the uses to which the snap switch herein described may be adapted. The circuits, however, and their control through these switches, will be obvious to those skilled in the art.

We have herein shown and described specific embodiments of snap switches, but desire it understood that these are preferred forms only, and that the invention itself is of broader scope and that the switches themselves may be modified within the spirit of the invention and the scope of the appended claims. For instance, a circuit selective function may be imparted to a single switch of the type shown in Figs. 1 and 2 by providing say, four contact fingers with their contact ends in different transverse planes and by providing the contact bridging plunger with four contact portions and with a fifth insulated portion arranged to engage one of the contact fingers in one position of the plunger, these fingers in another position all making contact with the plunger. By this means multiple and series circuits can be created for dimming or brightening lights. Or again, in a multiple unit switch of the type shown in Fig. 8, one of the switch units may be arranged as described with reference to Fig. 8, and the other may have its three contact fingers in different planes, the plunger having three contact portions and an adjacent insulated portion arranged to engage one of the contact fingers in one position of the bridging plunger, these contact fingers in another position of the plunger all making contact therewith. This will enable the

switch to be used with two overlapping circuits permitting a selection of circuit by the operation of the plunger just described into one or the other of such positions. From this it will be seen that various effects and structures are permissible within the principle and scope of the invention described.

What we claim is:

1. A quick-throw plunger switch comprising a substantially tubular insulating base having closed sides, a closed bottom and an open front end, spring contact fingers mounted on said closed bottom inside said tubular base, internally screw threaded tubular anchorages engaged with the base portions of said contact fingers and extended out through the bottom of the base, external terminal screws outside the base engaged in said threaded tubular outwardly extended anchorages, a face plate secured to the base and closing the open front end of the same, said face plate having a guide opening therethrough and a plunger working in the guide opening in said face plate, provided with conducting and non-conducting portions engaging the spring contact fingers.

2. A plural unit quick throw switch comprising a plurality of associated switch units, each of said units comprising a hollow insulating base having a closed bottom and an open front end, spring contact fingers seated in said hollow base, internally screw threaded tubular anchorages secured to the base portions of said contact fingers and extended out through the bottom of said base, external terminal screws on the bottom of the base engaged in said threaded tubular outwardly extended anchorages and a plunger provided with conducting and non-conducting portions to engage the spring contact fingers, a face plate secured to the insulating bases of the several units and closing the open front ends of said bases, said face plate having guide openings therethrough for the plungers of the several units, and a bus bar connecting the several units and secured to the bottoms of the units by the terminal screws of the units.
